PATIENT-LIFT

Albert L. Bresch, University City, Mo.

Application July 17, 1944, Serial No. 545,210

8 Claims. (Cl. 5—86)

1

This invention relates in general to certain new and useful improvements in patient-lifts for use in hospitals and in the field in the care of the sick and wounded.

The problem of lifting, turning and otherwise handling the sick has, in the past, been dealt with by the development of a great number of very complicated and expensive beds, such as fracture beds and the like. In addition, beds with "built-in" patient lifts of a very cumbersome type have from time to time been proposed. Except for very specialized and unusual cases, however, such devices have proven ineffective. In the first place, it is almost prohibitively expensive to outfit a hospital with such specially constructed beds and even apart from the matter of expense, such beds do not possess some of the features of adjustability necessary in the day to day care of the ordinary type of patient who is either convalescing or is suffering from a non-critical illness. Furthermore, a patient-lift is not needed for the entire period during which a patient is hospitalized so that the equipment is idle for much of the time.

For these reasons there has long been a vital need for a patient-lift which is completely portable and can be readily moved from place to place and set up for use quickly, simply and as an adjunct or accessory to a standard hospital bed, or, where necessary, may be used in the field in caring for wounded soldiers from a battle area.

It is, therefore, the primary object of the present invention to provide a patient lift, which is simple and economical in construction; and which is capable of being rapidly and conveniently disassembled, or "knocked down" as it may be said, so as to be reduced to a very compact size and shape for easy portability from place to place in a hospital or even from house to house by nurses on house duty.

It is a further object of the present invention to provide a device of the type stated which is lightweight and yet rugged and durable.

It is an additional object of the present invention to provide a device of the type stated which is relatively inexpensive in both initial cost and maintenance, and which may be used as an adjunct or accessory to a standard hospital bed without materially interfering with the normal operation or functions of the bed and without "cluttering up" the bed with unsightly, unsanitary and unremovable gadgets which reduce efficiency and hamper rather than aid the nurse in the performance of her duties.

And with the above and other objects in view, 55 beds are being used.

2

my invention resides in the novel features of form, construction, arrangement, and combination of parts presently described and pointed out in the claims.

5 In the accompanying drawings (three sheets)—

Figure 1 is a top plan view of a patient-lift constructed in accordance with and embodying the present invention;

10 Figure 2 is a side elevational view of the patient-lift;

Figures 3, 4, and 5 are sectional views taken respectively along lines 3—3, 4—4, and 5—5 of Figure 1;

15 Figure 6 is a sectional view taken along line 6—6 of Figure 2;

Figures 7 and 8 are sectional views taken respectively along lines 7—7 and 8—8 of Figure 1; and

20 Figure 9 is a fragmentary sectional view of a modified form of handle mechanism forming a part of the present invention;

Figure 10 is a fragmentary sectional view of a modified form of splined lift screw forming a part

25 of the present invention;

Figure 11 is a transverse sectional view taken along line 11—11 of Figure 10;

Figure 12 is a plan view of a modified form of patient-lift constructed in accordance with and

30 embodying the present invention;

Figure 13 is a fragmentary view partly broken away and in section illustrating in more detail the modified form of patient-lift shown in Figure 12; and

35 Figure 14 is an exploded view of the modified form of patient-lift shown in Figure 12.

Referring now in more detail to the drawings which illustrate a preferred form of the present invention, the patient-lift comprises a central 40 H-shaped frame 1, consisting of two T-shaped elements 2, 3, formed preferably of seamless tubing of square cross-sectional shape. The element 2 integrally includes a longitudinal side-rail forming member 4 and a lateral member 5. Similarly, 45 the element 3 comprises a side-rail forming member 6, identical in size and shape with the corresponding member 4, and a lateral member 7 having a cross sectional size adapted for slidably telescopic fit, as at a, the member 5 being provided

50 with a suitable set screw 8 for holding the lateral members 5, 7, in any selected position of adjustment. It is, thus, possible to adjust the transverse width of the main frame 1 to fit beds of varying width where beds other than standard hospital

Internally, the members 4, 5, 6, 7, of the main frame 1 are provided with shaft-bearing sleeves 9, 10, 11, 12, 13, and 14, substantially as shown in Figure 6. Rotatably mounted in, and extending through, the shaft-bearing 11 is a cross shaft 15 provided at its outer end with a bevel gear 16 and at its other end with a collar 17 bearing against the adjacent face of the shaft-bearing 11 to prevent lengthwise translation of shaft 15. At its inner end the shaft 15 is integrally provided with an axially extending sleeve 18 which projects into the lateral member 7 of the frame element 6 and is of rectangular cross section for slidably receiving the rectangular end 19 of a companion cross shaft 20 which is in turn rotatably mounted in the bearing sleeve 12 and held against lengthwise shifting movement by suitably pinned collars 21, 21'. At its outer end the shaft 20 is provided with a bevel gear 22 and then projects through an aperture 23 formed in the outer face of the frame member 6, terminating in a conventional crank-shaped handle 24. Rotatably mounted in the shaft bearings 9, 10, are identical jack shafts 25 each provided on its end with bevel gears 26, 27, the latter being in meshing engagement with the bevel gears 16. Similarly mounted in the shaft bearings 13, 14, are identical jack shafts 28 provided on their ends with bevel gears 29, 30, the latter being in meshing engagement with the bevel gear 22.

It should be noted in this connection that the bevel gears 26, 29 are so positioned as to project a short distance outwardly from the ends of the side-rail forming members 4, 6, all as best seen in Figures 3 and 6.

Also provided are four identical leg members 31, each formed integrally of seamless square-section tubing of substantially the same type and shape as the tubing employed in fabricating the main frame 1. Adjacent the upper end and projecting laterally from one side face of each leg 31 is a short sleeve 32, sized for snug fitting telescopic engagement over one of the ends of the side-rail forming members 4, 6. Fixed within the leg member 31 is a bearing sleeve 33 provided for loosely receiving a vertical lift screw 34 which bears upon the upper face of the shaft bearing 33, and is provided with an integrally formed bevel gear 36 adapted for meshing engagement with one of the projecting bevel gears 26, 29. Also fixed within the leg 31 adjacent the upper end thereof is an upper shaft bearing sleeve 37 having at its lower end an integrally formed, diametrically reduced extension 38 which bears at its lower end against the upper face of the bevel gear 36 and thus holds the bevel gear operatively in place. The lift screw 34 extends loosely through the bearing sleeve 37 and projects upwardly therefrom and at its projecting end is provided with a head member 39 having a diametral bore 40, all as best seen in Figures 3 and 8 for purposes presently more fully appearing.

It should be noted that each of the sleeves 32 of the legs 31 will fit any one of the ends of the side-rail forming members 4, 6, and similarly the bevel gears 36 will mesh and engage any one of the bevel gears 26, 29, so that the legs are completely interchangeable. Furthermore, by reason of the rectangular cross-section of the tubing the legs 31 will remain in upright position at 90° to the plane of the main frame 1 when the patient-lift is set up and it is impossible for the legs to collapse accidentally under the frame when the patient-lift is in actual use. In addition, the sleeves 32

and the ends of the side-rail forming members 4, 6, are provided with transversely aligned apertures, as at b, for receiving movable securing pins 41 as shown in Figure 8, whereby the legs and main frame may be securely held together when the device is set up in operative position. It will, of course, be obvious that the pins 41 may be quickly removed when the device is being disassembled or "knocked down."

10 Provided for removable sliding insertion through the bored holes 40 of the head members 39 are sturdy elongated rods 42 and looped around and extending more or less horizontally between the rods 42 are continuous webbing bands or straps 43 upon which the body of the patient may rest, as best seen in Figures 1 and 5. Any desired number of these bands 43 may be employed and they may be shifted longitudinally of the device to various portions of the patient's body as the 15 particular circumstances may require and demand. In fact, preparatory to using the patient-lift any suitable number of bands 43 may be pushed carefully under the body of the patient so that the looped ends will hang down somewhat 20 over the edge of the mattress on either side. Then, the rods 42 may be threaded through such looped ends and inserted through the bored holes 40. When in such inserted position, the rods 42 not only support the bands 43 but effectively hold 25 the lift-screws 34 from turning, so that they will 30 be propelled upwardly upon rotation of the bevel gears 35.

In some cases it is undesirable to have the handle 24 located on the side of the device in 35 the region of the center of the bed. It is accordingly possible to provide a modified form of end 36 post or leg 31', which is substantially identical in all respects to the legs 31 except that it is integrally provided in its outer face with a bulge or 40 enlargement 44 designed and meshed to provide a bearing 45 for rotatably receiving a stub shaft 46 which extends therethrough. Pinned or keyed upon the near end of the stub shaft 46 is a main 45 drive bevel gear 47 for engagement with a bevel gear 36; the latter corresponding in every respect to the previously described bevel gears 36 and similarly pinned or keyed to the outer end of the stub shaft 46 is a conventional crank handle 48, all as best seen in Figure 9.

50 It may also be desirable to avoid the use of the rods 42 to prevent the lift screws 34 from rotating, although this is the most economical and 55 convenient manner of construction. Therefore, it is also possible to provide each of the legs 31 at its upper end with a modified form of bearing sleeve 37' having a central screw receiving bore 49, which is integrally provided with an axial spline 50, for slidably engagement in a 60 groove or weight 51 milled lengthwise in the modified form of lift screw 34', all as best seen in Figures 10 and 11. As a result of this method of construction the lift screw 34 will shift vertically upon rotatable movement of the bevel gear 36 without imposing any twisting stress upon the 65 rod 42.

If desired, a patient-lift may be fabricated of 70 tubing of circular cross section as shown in Figure 12 and is substantially similar to the previously described embodiment of the present invention 75 comprising an H-shaped main frame 1' formed of two T-shaped sections 2', 3', having side-rail forming members 4', 6', and interfitting or telescoping lateral members 5', 7'. The lateral member 5' is provided with a pair of laterally inwardly extending diametrically opposed

pins 52 for slidable cooperation with a pair of axially extending diametrically juxtaposed slots 53, formed in the telescoping end of the lateral member 1' so as to permit width-wise adjustment of the main frame 1 and at the same time prevent rotation of the two lateral members, one within the other. Similarly, the leg receiving ends of the side-rails 4', 6' are provided with inwardly projecting radial pins 54 for cooperation with axially extending diametrically juxtaposed slots 55 formed in the tubular extensions 56 of the leg members 31''. The tubular extension 56 are sized for fitting telescopically within the outer ends of the side-rails 4', 6' and the latter are arcuately cut away as at c for snug fitting edgewise engagement with the cylindrical surface of the leg member 31''. The cooperation between the pins 54 and the slots 55 prevent the legs 31'' from accidentally rotating with respect to the side-rails 4', 6' when the patient-lift is set-up for actual use. The leg receiving ends of the side-rails 4', 6', and the tubular extensions 56 are provided with registering apertures 57 for receiving removable locking pins 41', all as best seen in Figures 13 and 14.

It will be apparent that the patient-lift of the present invention is simple, rugged and economical in construction and may be quickly and conveniently "knocked down" or set up and easily carried from place to place as circumstances may require. It may be adjusted to fit beneath and around hospital beds and other beds in which sick patients may be placed. For example, two or three patient-lifts of the type described may be kept on each hospital floor and may be quickly set up as an adjunct or accessory device around a hospital bed while the patient is critically ill and is, therefore, difficult to handle. The relationship between a hospital bed and the patient-lift when the latter is in operatively set-up position, is shown in Figures 1, 2, and 5, wherein the hospital bed is depicted in desired lines. After the patient has recovered sufficiently to be able to move himself or at least to assist the nurse in moving him, the patient-lift may be disassembled quickly and conveniently and transported to the bedside of another critically ill patient or to storage as the need may be.

It should be understood that changes and modifications in the form, construction, arrangement, and combination of the several parts of the patient-lift may be made and substituted for those herein shown and described without departing from the nature and principle of my invention.

Having thus described my invention, what I claim and desire to secure by Letters Patent is:

1. A portable patient-lift comprising an H-shaped main frame consisting of two tubular side-rail-forming members transversely connected by a telescoping cross-member having means for securing the cross-member in any of its several positions of adjustment whereby the transverse width of the frame may be varied, four leg-members each provided with a lateral tubular sleeve for snug-fitting telescoping engagement on the ends of the side-rail-forming members for detachable securement thereto, elevating means in the leg-members, and manually operable driving means in the main frame for operative engagement with the elevating means when the leg-members are secured in place on the main frame.

2. A portable patient-lift comprising an H-shaped main frame consisting of two tubular

side-rail-forming members transversely connected by a telescoping cross-member having means for securing the cross-member in any of its several positions of adjustment whereby the transverse width of the frame may be varied, four leg-members each provided with a lateral tubular sleeve for snug-fitting telescoping engagement on the ends of the side-rail-forming members for detachable securement thereto, elevating means in the leg-members, manually operable driving means in the main frame for operative engagement with the elevating means when the leg-members are secured in place on the main frame, and means for optionally locking the leg-members in place on the frame.

3. A portable patient-lift comprising an H-shaped main frame consisting of two tubular side-rail-forming members transversely connected by a telescoping cross-member having means for securing the cross-member in any of its several positions of adjustment whereby the transverse width of the frame may be varied, four leg-members each provided with a lateral tubular sleeve for snug-fitting telescoping engagement on the ends of the side-rail-forming members for detachable securement thereto, elevating means in the leg-members, means operatively mounted in the main frame for interconnecting the several elevating means when the leg-members are secured in place on the main frame, said last named means including a lengthwise adjustable transverse shaft extending axially through cross-member of the frame, and manually actuatable means for driving the elevating means.

4. A portable patient-lift comprising an H-shaped main frame formed of tubing of square cross-section and including two side-rail members transversely connected by a telescopically adjustable cross-member having means for securing the cross-member in any of its several positions of adjustment whereby the transverse width of the frame may be varied, four leg-members each provided with a lateral tubular sleeve for snug-fitting telescoping engagement on the ends of the side-rail-forming members for detachable securement thereto, elevating means in the leg-members, and manually operable driving means in the main frame for operative engagement with the elevating means when the leg-members are secured in place on the main frame.

5. A portable patient-lift comprising an H-shaped main frame formed of tubing of arcular cross-section and including two side-rail members transversely connected by a telescoping cross-member having means for securing the cross-member in any of its several positions of adjustment whereby the transverse width of the frame may be varied, each of said side rails being provided at its ends with inwardly projecting pins, four leg-members each provided with a lateral tubular sleeve for snug-fitting telescoping engagement on the ends of the side-rail-forming members for detachable securement thereto, and having slots for engaging the pins whereby the legs and rails are firmly held in a predetermined angular relationship, elevating means in the leg-members, manually operable driving means in the main frame for operative engagement with the elevating means when the leg-members are secured in place on the main frame, and means for optionally locking the leg-members in place on the frame.

6. A portable patient-lift comprising a main frame having four outwardly presented end por-

tions of rectangular cross-section, leg-members having laterally presented portions sized and shaped for telescopically interfitted and interchangeable engagement with any one of the end portions of the frame, elevating means operatively mounted in the leg-members, and manually actuatable driving means mounted in the frame for driving engagement with the elevating means when the leg-members are operatively secured to the main frame and adapted to disengage readily when the leg-members are removed from the main frame.

7. A portable patient-lift comprising a main frame having four outwardly presented end portions, leg-members having laterally presented portions sized for telescopically interfitted and interchangeable engagement with any one of the end portions of the frame, elevating means operatively mounted in the leg-members, manually actuatable driving means mounted in the frame for driving engagement with the elevating means when the leg-members are operatively secured to the main frame and adapted to disengage readily when the leg-members are removed from the main frame, and co-operably interengaging means on the telescopically interfitted portions of the legs and frame for holding the legs vertical when the frame is horizontal.

8. A portable patient-lift comprising a main frame having four outwardly presented end portions, leg-members having laterally presented

portions sized for telescopically interfitted and interchangeable engagement with any one of the end portions of the frame, elevating means operatively mounted in the leg-members, manually actuatable driving means mounted in the frame for driving engagement with the elevating means when the leg-members are operatively secured to the main frame and adapted to disengage readily when the leg-members are removed from the main frame, and co-operably interengaging pin-and-slot means on the telescopically interfitted portions of the legs and frame for holding the legs vertical when the frame is horizontal.
